UNITED STATES PATENT OFFICE.

ALOYS J. HOFFMAN, OF FREMONT, OHIO.

GROMMET-SETTING DEVICE.

Application filed November 17, 1925. Serial No. 69,650.

This invention relates to devices for setting those forms of separable fasteners commonly known in the art as turn-button grommets, wherein the fastener comprises 5 a prong carrying body portion, the prongs of which are adapted to pass through the receiving fabric and to be bent inwardly and engaged over a washer disposed on the opposite side of the material.

10 The invention has for an object to provide a device to set fasteners of the character stated, in which means are provided for forming a button receiving opening in the material, for locating the washer, and 15 for setting the body portion of the grommet in such a manner that the prongs thereof will be passed through the material and engaged over the washer, thereby firmly securing the body portion of the grommet 20 and the washer to the material, all of said means being actuated in a single operation of the device.

It is likewise an equally important object of the invention to provide a device of the 25 character mentioned wherein the lower die thereof is provided with a plurality of adjustably mounted dogs having the exposed surfaces thereof so formed as to deflect the free portions of the fastener prongs extended from the receiving material inwardly and with continued application of pressure thereto, to cause such prongs to be bent inwardly and clampingly engaged with the adjacent portions of the washer.

30 Yet another object of the invention is to provide the lower die of the device with means for receiving and positively retaining the washer of the grommet in proper position during the cutting or punching of an opening in the material and the deflection and inward bending of the fastener prongs thereover, thus, insuring proper assemblage of these grommets or fasteners as 35 well as the firm connection of same to the receiving material.

Other objects of the invention will be in part obvious and in part pointed out hereinafter.

In order that the invention and its mode 40 of operation may be readily understood by persons skilled in the art, I have in the accompanying illustrative drawings, and in the detailed following description based thereon, set out one possible embodiment 45 of the same.

In these drawings:

Figure 1 is a perspective view showing the relative arrangement of the dies, the material and the elements of a separable fastener or grommet;

Figure 2 is a vertical section through the device with the elements of the grommet about to be engaged;

Figure 3 is a similar view wherein the elements of the grommet have been engaged;

Figure 4 is an elevation of the upper die and punch;

Figure 5 is a horizontal section taken on the line 5—5 of Figure 4, showing the magnetized portion of the anvil portion;

Figure 6 is a similar section taken on the line 6—6 of Figure 4 showing the formation of the punch;

Figure 7 is a plan view of the lower die, and

Figure 8 is a vertical section through the lower die.

Having more particular reference to the drawings, in connection with which like characters of reference will designate corresponding parts throughout, the improved device may be stated to comprise opposed movable dies indicated for convenience at this time in their entirety by the numerals 80 1 and 2, the dies being arranged so that the die 1 is the lower while the die 2 is arranged thereabove. The upper die 2 carries an attaching shank 3 extended from the upper portion thereof in order that the 85 same may be suitably secured to the plunger or other corresponding means of an operating machine, not shown herein; while the lower die 1 is adapted to be removably supported upon a suitable bed upon such 90 operating machine.

The lower die 1 consists of a bed block or base 4, preferably circular in configuration and having a plurality of relatively spaced radially disposed pockets 5 formed 100 therein, the outer portions of said pockets opening onto the adjacent peripheral portions of the base 4 in order that deflecting dogs 6 may be slidably and snugly engaged 105 therein. These deflecting dogs 6 are substantially rectangular in configuration, having the inner extremities thereof curved as at 7 to correspond with the curvature of the inwardly disposed portions of the pockets 5, while the upper or exposed sur- 110

faces thereof are curved upon themselves as indicated at 8, these curved surfaces being disposed inwardly upon their respective dogs with regard to the bed block 4.

5 A substantially oval shaped opening 9 is formed between and approximately concentrically of the bed block 4 and serves to permit of the punching of an opening in the material receiving the fastener or grommet, in a manner hereinafter more fully described, during that time when the several portions of said grommet or fastener are being assembled and interconnected.

10 A cover plate 10 is provided the circular bed block 4 and, as will be noted, is formed with a peripheral flange 11, of such size and shape as to snugly engage over the upper portion of such circular bed block 4 in the manner as shown in the drawings, 15 whereupon fastening screws or similar devices 12 are passed through screw threaded openings formed therein and into binding engagement with adjacent portions of the peripheral surface of said bed block 4, 20 hence, connecting the top or cover 10 thereto and preventing movement of the same. In this way, it is manifest that the bed block 4 and its cap or cover 10 will be secured in assembled relation.

25 The cap or cover 10 is formed with a substantially oval shaped opening 13 of size and shape corresponding to the washer of the type of grommet to be assembled and fastened thereupon, thus, permitting of the placement of such a washer as indicated by the numeral 14 upon the bed block 4 in a position whereat the opening therein will be properly positioned with relation to the aforesaid oval opening 9 and likewise, that 30 said washer 14 will be so retained during the assembling, punching and connecting of the prongs of the body portion of the grommet or fastener over or with said washer 14.

35 In order that the dished or inwardly curved exposed faces of the various dogs 6 may properly perform their deflecting functions with engagement of the free extremities of the prongs of the body portion of the grommet therewith, pockets or recesses 40 are cut or otherwise formed in the cap or cover 10 about the oval opening 13 and in a manner to correspond to the arrangement of the pockets 5 and their respective dogs 6 upon the bed block 4. In this way, it is 45 obvious that the inwardly curved or dished exposed surfaces of the said dogs 6 will be in position to be properly engaged by the free extremities of the prongs upon the body 50 portion of the grommet at all times, one of these body portions being shown in the accompanying drawings for convenience, and designated at this time by the numeral 16; it being noted that such body portion is 55 provided with angularly extending marginal

fastening prongs 17 adapted to pierce the fabric receiving the device and to be then flexed or bent over the same and the washer 14 for effecting a clamp-like assemblage of the device upon such receiving material.

60 It is desirable that the dogs 6 with their curved or dished exposed surfaces 8 shall be adjustably secured in position with respect to the bed block 4 and the cover 10 and to this end, I engage in suitably screw threaded 65 openings formed in the peripheral flange 11 of said cap 10, a plurality of adjusting screws 18, the inner extremities of the shanks thereof being adapted to have binding engagement with the adjacent outer ends 70 of the corresponding dogs 6. Hence, because of the snug slidable engagement of these dogs in their particular pockets 5, it will be appreciated that the same may be adjusted vertically or angularly therein, 75 following which, their particular adjusting screws are engaged with the same and the dogs, accordingly, firmly secured in their properly adjusted positions.

80 The upper die is of the so-called anvil type, comprising a body portion 19, substantially oval in configuration and corresponding, somewhat, to the general configuration of the body portion 16 of the grommet to be assembled and fastened thereby. This body portion may be and preferably is magnetized in order that with arrangement of the body portion of a grommet in position thereupon, such portion will be 85 positively held in proper position upon the upper die 2 and by consequence, proper engagement of the extremities of the prongs 17 with the curved surfaces 8 of the dogs 6 will be insured. It is preferable, however, that this magnetized body portion 19 shall 90 be insulated from the operating or receiving machine and to effect this, an insulating washer or plate 20 is engaged over the upper side of said body portion and about the attaching shank 3.

95 The attaching shank 3, aforesaid, is snugly but removably received through an opening formed concentrically of the oval-shaped body portion 19 of the upper die 2 and carries a head-like oval portion 21 upon 100 the lower end thereof, such portion constituting the punch or fabric cutting portion 115 of the invention. In this connection, it will be noted that the punch 21 is of a configuration corresponding to that of the oval opening 9 and furthermore, that the same is of a size such as to permit of snug engagement and passage through such oval opening 9. Therefore, with downward movement of the upper die 2 in the operating machine, the punch 21 will enter the oval opening 9 and in so doing, will pass through the material receiving the grommet, thereby punching an oval shaped opening in the same, corresponding to the oval opening formed in 110 120 125 130

the body portion 16 and the fastener ring 14 of the grommet.

It is preferable that the punch 21 be provided with means for properly locating it with respect to the oval body portion 19 of the upper die 2, hence, insuring a proper engagement of the punch 21 in the oval opening 9 of the lower die 1. To effect this, oppositely disposed ribs 22 are formed upon the sides of the oval shaped punch 21 and are adapted to be slidably received in openings formed in the opposite sides of a collar like extension 23 carried upon the inner side of the oval body portion 19 of said upper die 2. Thus, it will be appreciated that with engagement of the rib 22 in the openings formed in the collar like extension 23, further movement as between the punch 21 and the oval body portion 19 will be prevented; therefore, that proper engagement of the punch 21 in the oval opening 9 of the lower die 1 will at all times be insured.

In operation of my improved invention and assuming that the upper and lower dies have been properly positioned upon a receiving or operating machine, the body portion of a grommet or similar fastener indicated for convenience by the numeral 16, is engaged with the under side of the oval shaped body portion 19 of the upper die 2, it being borne in mind that this oval body portion is magnetized and by consequence retains such body portion 16 of the grommet in engagement therewith. When so engaged with the body portion 19 of the upper die 2, the fastener element 16 will have the oval shaped punch 21 extended through and downwardly beyond the oval opening formed therein, while the attaching prongs 17 of such element will be disposed downwardly and located in direct alignment with the curved exposed faces of the various dogs 6 arranged upon the lower die 1. Also, a washer 14 is laid upon the bed block 4 of the lower die 1, within the opening provided therefor in the cap or cover 10, the positioning of this washer upon the bed block 4 being in a manner to correspond to the positioning or placement of the body portion 16 of the fastener upon the upper die 2. The material receiving the grommet or separable fastener, that is, the material upon which this particular fastener is to be secured, indicated at this time for the purpose of convenience by the reference character M is now arranged between the upper and lower dies 2 and 1. At this time, the upper die is moved sharply downwardly causing the punch 21 to be passed through an adjacent portion of such material M during its engagement in the oval opening 9 of the lower die 1. Simultaneously, the penetrating prongs 17 of the body portion 16 of the grommet or separable fastener will be passed through corresponding portions of said material M, and the free extremities of these prongs will be engaged with the inwardly curved or dished exposed surfaces of the various dogs 6, adjustably secured in their respective pockets upon the bed block 4 of the lower die. With continued downward movement and the application of pressure to the upper die 2, the body portion 16 of the grommet or separable fastener will be brought down onto the adjacent surface of the material M while the free extremities of the penetrating prongs 17 will be deflected inwardly over the inwardly curved exposed portions of the adjustably exposed dogs 6, thereby flexing or bending the extremities of said prongs 17 over the washer 14 retained, during this time, in the oval-faced opening 13 formed in the cap or cover 10. Sufficient force or pressure is of course directed upon the upper die 2 to effect a positive clamping as between the body portion 16 and the washer 14 of the grommet or separable fastening, and by consequence, the firm engagement of the inwardly bent extremities of the penetrating prongs 17 over the adjacent portions of said washer 14. In this way, it will be appreciated that the assembled grommet will be firmly secured to the receiving material M and by consequence, its disengagement from such material either through relative movement or similar objectionable features will be avoided. The upper die 2 is now returned or raised to its initial or normal position whereupon the material M is rearranged with respect to the device, another body portion 16 engaged with the upper die 2 and a washer with the lower die 1 whereupon the device is ready for further operation.

Manifestly, the construction shown is capable of considerable modification, and such modification as is within the scope of my claims, I consider within the spirit of my invention.

I claim:

1. A device of the character described, comprising opposed relatively movable dies, one thereof having a plurality of relatively spaced and radially adjustable deflecting surfaces on its inner face, the opposite die consisting of an anvil portion cooperable with said deflecting surfaces of the first die, and a punching means extending therefrom and engageable in a corresponding opening formed in the first die.

2. A device of the character described, comprising opposed relatively movable dies, one thereof having a plurality of relatively spaced and independently radially adjustable deflecting means on its inner face, said die having an opening therein between said deflecting means, the opposite die consisting of an anvil portion cooperable with said deflecting means of the first die, and a punching means carried by and extending there-

from slidably engageable in said opening of the first die.

3. A device of the character described, comprising opposed relatively movable dies, 5 one thereof having a plurality of relatively spaced radially disposed pockets formed therein, a plurality of dogs slidably received in said pockets having inwardly curved upper faces, means on said die engageable 10 with the dogs for securing the same in relatively adjusted positions, said die having an opening therethrough between the pockets therein, the opposite die consisting of an anvil portion cooperable with said dogs of 15 the first die, and a punching means carried by and extended therefrom engageable in said opening of the first die.

4. A device of the character described, comprising opposed relatively movable dies, 20 one thereof having a plurality of dogs movably arranged in one of its sides, a cap engaged over said die, means carried on the cap for engagement with the said dogs, whereby to secure the same in relatively ad- 25 justed positions, said cap having openings therein for exposing the upper faces of said dogs and an oval opening forming a washer receiving seat, said die having an opening extending therethrough and arranged be- 30 tween said dogs, the opposite die consisting of an anvil portion cooperable with said dogs and with their ring receiving openings in 35 said cap, and a punch carried by and extending from said anvil portion snugly engageable in the opening in said first die.

5. A device of the character described

comprising opposed relatively movable dies, one of said dies consisting of a bed block having a plurality of relatively spaced radially disposed pockets formed therein and opening onto the peripheral surface thereof, a plurality of dogs snugly and slidably engaged in said pockets and having their upper faces curved inwardly, the central portion of said bed block having an opening formed therein between said pockets, a cap having a peripheral flange snugly engageable over the upper portion of said bed block, said cap having a centrally arranged opening therein and other openings about the same for exposing the inwardly curved upper sides of said dogs, means for securing the cap to the bed block, other means on the cap for securing said dogs in relatively adjusted positions with respect to said bed block, the opposite die comprising an anvil portion of a configuration corresponding to the openings formed centrally of said cap, said body portion being magnetized, a shank extending 60 through an opening formed in the anvil portion, a punch head carried upon the inner end portion of said shank and extending from and beyond said anvil portion for snug engagement in the opening in said bed block, and means carried on the punch engageable 65 with portions of the anvil portion for preventing relative rotary movement therebetween.

In witness whereof I have hereunto set my 70 hand.

ALOYS J. HOFFMAN.
